UNITED STATES PATENT OFFICE.

WILLIAM P. KOOKOGEY, OF BROOKLYN, NEW YORK, ASSIGNOR TO THE KOOKOGEY ELECTRIC COMPANY.

RAILWAY-SIGNAL.

SPECIFICATION forming part of Letters Patent No. 396,749, dated January 29, 1889.

Application filed June 7, 1887. Renewed June 9, 1888. Serial No. 276,568. (No model.)

To all whom it may concern:

Be it known that I, WILLIAM P. KOOKOGEY, of Brooklyn, in the county of Kings and State of New York, have invented certain new and useful Improvements in Electric-Lighting Apparatus for Way-Station, of which the following is a specification.

My invention relates to means for lighting way-stations of railways in advance of, during, and, if necessary, for a short time after the passage of a train by the station, the purpose being to render unnecessary the attendance of an agent at the station or stations during the later hours, when only an occasional passenger boards or leaves the train at such stations. Under existing systems it is necessary either to have an agent present at the station to light the same whenever a train is due, or else to leave the station dark, to the annoyance and inconvenience of passengers. The former plan involves considerable expense and unnecessary labor, and the latter plan is of course unsatisfactory to the traveling public. To remedy these difficulties I adopt the construction represented in the accompanying drawings, in which—

Figures 1 and 2 are diagrams illustrating the circuits and circuit-closing devices which I employ to secure the lighting of the lamps at and during the time required and their extinction when the need for them is passed, Fig. 1 showing the lighting-circuit closed, and Fig. 2 showing the same broken or open.

A and B indicate the rails of the track, the rail B being provided with two insulated sections, 1 and 2, the remainder of the track being uninsulated. From the insulated section 1 a wire or conductor, a, passes to and connects with the helix of an electro-magnet, C, thence to a battery, D, and finally to the rail A or other ground-connection. Facing the electro-magnet C is a pendulous or movable circuit-closer, E, carrying an armature, b, which, when the magnet is energized, is attracted thereby, and completes a local circuit containing the lamps to be lighted and the battery or other source of electricity for supplying the necessary current to the lamps. This circuit is formed by the circuit-closer E and contact spring or plate c, line or conductor d,

lamp or lamps F, line e, and battery G, which latter is connected by a short line, f, with the circuit-closer E. From this it will be seen that whenever the circuit-closer E makes contact with the contact spring or plate c the circuit will be closed from battery G through the local circuit and the lamps F, rendering the lamps luminous; and it will also be seen that they will continue luminous so long as the battery or generator continues to furnish the necessary current and the circuit-closer E maintains contact with the finger c.

The circuit of which insulated section 1 forms a part is only closed for a brief time, or while the train is passing over it, and is located at such distance in advance of the station as to cause lights to be lighted in advance of the arrival of the train, the magnet C becoming inactive as soon as the train leaves the insulated section 1 and destroys the circuit which it had previously completed through the bridging of the rails by its wheels and axles.

The circuit-closer E should be so arranged that it will stand in any position to which it is moved—a result which may be accomplished either by applying slight friction thereto or by making the portion above the pivot slightly heavier than the portion below the same, so that it shall act as a counter-balance to hold the circuit-closer in one or the other of these two positions as soon as the counter-weight passes the vertical plane of the pivot, though I prefer to arrange the circuit-closer to swing horizontally, in which case it will stand where placed.

For the purpose of extinguishing the lights when the train leaves the station or reaches a suitable distance beyond the same I employ a second electro-magnet, H, one end of the helix of which connects by a wire or conductor, g, with insulated section 2, and the other end of which is connected by similar wire or conductor, h, with the wire or conductor a at a point between electro-magnet C and battery D, so that when the rails A B are bridged by the wheels and axles of the train on the insulated section 2 a circuit will be completed through said wheels and axles, the insulated section 2 of rail B, wire g, elec-

tro-magnet H, wire h, battery D, line a, and rail A or ground-connection, thereby energizing magnet H and causing it to attract the armature b of the circuit-closer E. This construction causes the circuit-closer to move away from electro-magnet C and out of contact with the contact-plate c, thus breaking the light or lamp circuit and causing the lamps to go out or cease to be luminous.

10 The device is extremely simple and efficient in practice.

Separate batteries may of course be used for the electro-magnets C and H, though for the sake of economy I prefer to employ but 15 one for that purpose.

It will also be seen that the lamp-battery G may be utilized to energize the electro-magnets C and H, as well as furnishing the necessary current for the lamps; but this is not 20 deemed desirable, because of the strength and volume of current required, and because, also, of the greater danger of failure of the apparatus to operate.

Having thus described my invention, what I 25 claim is—

1. In combination with a local electric circuit containing a light-giving device and located at the station or point to be lighted, a second circuit adapted to be closed by a train 30 passing along the track at a point in advance of the station or light, an electro-magnet included in said second circuit, and a circuit-closer included in the light-circuit, and adapted to be attracted by the electro-magnet 35 and to complete the light-circuit whenever the second circuit is completed through the bridging of the rails by the train.

2. The combination of rails A B, the latter provided with insulated section 1, an electro-magnet, C, and battery D, connected in circuit with insulated section 1 and with ground or rail A, a light-circuit containing the circuit-closer E and contact c, and an armature carried by the circuit-closer and placed within 45 the field of magnet C, whereby the circuit-closer is attracted and caused to complete the light-circuit when the rails are bridged at the section 1.

3. In combination with a railway-track 50 having insulated rail-sections, one in advance of the point to be lighted, a local light-circuit, a circuit-closer included in said circuit, electro-magnets arranged to move the circuit-closer in opposite directions, and two independent circuits, each including one of the 55 insulated sections and one of the electro-magnets, substantially as shown, whereby the entrance of a train upon the first insulated section is caused to effect the closing of the

light-circuit and the entrance of the train 60 upon the second insulated section is caused to break or destroy the light-circuit.

4. In combination with lines A and B, the latter having insulated sections 1 and 2, wire or conductor a, connected at one end with the 65 insulated section 1 and at the other end with rail A or other ground-connection, electro-magnet C, a battery, D, included in said conductor a, electro-magnet H, having one end of its helix connected by a line or conductor, 70 g, with section 2, and its other end connected by a line or conductor, h, with a battery, which is in turn connected with the rail A or other ground, wires d e f, lamps F, and battery G, constituting a local light-circuit, a circuit-closer, E, and contact-spring c, for completing said light-circuit, the armature b of the circuit-closer being located between the 75 magnets C and H, all substantially as shown and described.

5. In combination with an electric lamp and a local circuit therefor, a circuit-closer included in said circuit, an electro-magnet adapted to attract the circuit-closer and to complete the light-circuit, lines or conductors 85 extending from the electro-magnet to an insulated section of the rail in advance of the light, and a ground-connection, whereby the entrance of a train upon the insulated section is caused to energize the electro-magnet and 90 complete the light-circuit.

6. In combination with an electric light and an electric circuit therefor, including a battery or other generator, a circuit-closer included in the light-circuit, electro-magnets 95 arranged to act upon the circuit-closer and move it in reverse directions, and two independent circuits, each including a battery or electric generator and an independent insulated section of the track, one of said sections 100 being located in advance of the lamp, whereby the entrance of a train upon the first insulated section is caused to complete the circuit through one of said electro-magnets, which thereupon attracts the circuit-closer 105 and completes the light-circuit, and the entrance of the train upon the second of the insulated sections is caused to complete the second circuit and move the circuit-closer to destroy the light-circuit, substantially as set 110 forth.

In witness whereof I hereunto set my hand in the presence of two witnesses.

WM. P. KOOKOGEY.
